UNITED STATES PATENT OFFICE.

SERGE DE PROCAUDINE-GORSKY, OF GRANSTAD, KONNERUD, NEAR DRAMMEN,
NORWAY.

PRINTING APPARATUS FOR THE PRODUCTION OF DIAPPOSITIVES.

1,413,873.

Specification of Letters Patent. Patented Apr. 25, 1922.

Application filed July 17, 1919. Serial No. 311,686.

To all whom it may concern:

Be it known that I, SERGE DE PROCAUDINE-GORSKY, a Russian subject, residing at present in Granstad, Konnerud, near Drammen, Norway, have invented certain new and useful Improvements in Printing Apparatus for the Production of Diapositives; and I do hereby declare the following to be a full, clear, and exact description of the invention, 10 such as will enable others skilled in the art to which it appertains to make and use the same, reference being had to the accompanying drawings, and to letters or figures of reference marked thereon, which form a 15 part of this specification.

This invention has for its object a printing apparatus for the production of diapositives.

In making coloured diapositives by repeatedly applying to a diapositive lamina 20 various emulsions for the prints of the negatives, which are to be taken one after another—a process which is the object of a concurrently filed, companion application 25 Serial No. 311,684, it is necessary to remove the diapositive plate after each print has been made in order to give it the necessary treatment. In order to obtain good results —viz: faultless coloured diapositives—after 30 this treatment, care must be taken that each succeeding print coincides exactly with the preceding one.

By means of the apparatus which is the object of the present invention exact registering of the prints with the original is obtained; in other words, this apparatus renders it possible to take any desired number of exactly identical diapositive prints. To attain this it is only necessary that the glass-plates intended for the diapositive pictures have ground edges. In grinding the plates it does not matter much, if the edges of the plate are not exactly in angle, but it is of importance only that the 45 edges have no such unevenness as would render them liable to break by the repeated inserting and taking out of the plate and whereby a removal or shifting of the position of the plate in the apparatus might be 50 caused.

The apparatus is arranged in such a way that the correct adjustment of the diapositive plates with ground edges is done automatically, wherefore no special attention or 55 experience is required from the attendants.

After having made the desired number of diapositives from a certain negative (a negative print taken through a screen of a certain colour) and prepared the latter for the next printing, the picture of such diapositive is placed in register with a second negative (three of such being in all,) the two are superposed and the printing of the next diapositive is made by simply placing them in the same frame and then exposing 60 to light. The same adjustment is made before the third negative is printed, so that only three adjustments of the negative and diapositive plates are necessary for making any desired number of coloured diapositives 65 after the three-colour system. 70

An apparatus constructed according with the invention is illustrated in the annexed drawing.

Fig. 1 is a plan view of a board or table, 75 which can be placed in any desired angle, and to which a device is fitted for the printing of diapositives in accordance with the present invention. Fig. 2 is a sectional view through the vertical center-line of the board. 80 Figs. 3 and 4 are sectional views on the lines 3—3 and 4—4, respectively, of Fig. 1. Fig. 5 is a side elevation of the apparatus, showing same in two different working positions of the board. When in the position indicated in full lines the putting in and removal of the diapositives are effected, whereas the adjustment of the negatives to be copied in respect to the diapositive is made 85 in the position shown in dotted lines. 90

Referring to Fig. 5 of the drawing, there is shown a table E, supported upon a stand F, and to which a board O of wood or other suitable material is connected by hinges 21 for upward and downward swinging movement. The board may be held in adjusted position by means of clamping screws 37, which engage in slots 36 formed in a pair of rods 35 pivoted at one end to the side edges of the board. 95

The said board is provided with an opening G (Figs. 2, 3 and 4); and to the inner face of the board behind said opening there is fixed a metal plate 60, while a frame 1 having a depending extension or arm 2 is 105 attached to the outer face thereof. The lower end of arm 2 carries a pivot 3 on which is mounted a sector-shaped member 6 located at one end of a crank 4, the other end of which terminates in a bent portion 110

or handle 5. Sector 6 is formed with a rearwardly-disposed spiral cam 7 for coaction with a nose 8 on a supporting arm 9, which is designed to swing toward and from the frame 1 and carries with it a plate 16 to be moved into and out of said frame. A spring 11, which encircles pivot 3, tends to force said sector against a nut 12 carried by said pivot, whereby the position and distance of the crank in relation to board O may be regulated.

To enable the movements of the supporting arm 9, its lower end is forked and mounted on a pair of spaced pivots 10 which are arranged upon the end of the frame arm 2 with their axes in alinement and at right angles to the axis of pivot 3. When crank 4 is swung downward from its full-line to its dotted-line position (Fig. 1), arm 9 will be permitted to swing outwardly away from frame 1, either gravitally or by being shifted manually; but when the crank is moved in an upward direction, i. e., from dotted-line to full-line position, cam 7 will act upon nose 8 to forcibly swing said arm toward said frame, as will be understood.

Stops 13 and 15 are provided to limit the movements of the crank in opposite directions, the upper stop 13 having associated with it a spring-actuated pin or bolt 14 which serves to retain the crank in its upper position. The lower stop 15 preferably has a movable mounting to permit it to be shifted from one position to another and thereby vary the range of movement of the crank; said stop being here shown as carried by a swinging arm 15° mounted on a pivot 20, so that it may be moved from its full-line position to its dotted-line position 40 15'. The crank is offset or bent adjacent its pivot end, as indicated in Fig. 5, in order that when the stop occupies the last-mentioned position, this bent or offset portion will clear said stop and enable the crank to 45 be moved beyond its dotted-line position sufficiently far to effect a complete disengagement of the parts 7 and 8. Arm 9 may then be swung away from frame 1, for instance into the dotted-line position represented in Fig. 5; and if the board occupies the tilted position shown in full lines in that figure, the movement of said arm will take place automatically, due to gravity.

The plate 16 above referred to is provided upon its inner face with a cushion 17 of felt or similar material which is directly attached to a disk 18. The latter fits adjustably within a recess, (Figs. 3 and 4) formed in the said inner face of plate 16 and has 60 connected to it a screw 19 for effecting its adjustment. The diapositive D is adapted to be positioned against this cushion 17 prior to its introduction into printing position in frame 1, and means are provided for 65 centering the diapositive and for retaining

it in place, all as hereinafter explained. Frame 1 is arranged obliquely or diagonally on board O—i. e., at an angle of about 45° to the vertical center line of the board, which latter has a correspondingly arranged 70 groove 22 (Fig. 1) formed in its outer face and adapted to be closed at its ends by covers 23 and 24, said groove extending beneath the frame and having a width equal to that of the negatives N from which the 75 diapositive prints are to be made. The negatives are placed under frame 1 and then clamped between the latter and a thick glass plate 25 which is supported on rubber cushions 27 fixed in a swinging frame 26 80 which in turn, is mounted on a pivot 28 (Fig. 3) suitably disposed within opening G and connected to frame 1, rubber strips or cushions being also applied to the rim of the frame on the inside thereof to avoid injury to the negatives. Frame 26 is formed with an extension carrying a bolt or screw 29 which projects outwardly through an opening in the fixed frame 1 and carries a nut 30, such arrangement enabling a relative adjustment between the two frames, as will be understood, which permits the glass plate 25 to be pressed against the negative plate, and the latter, in turn, against the fixed frame. 95

An electric lamp 33 provides the light necessary for printing, and is disposed within a frusto-conical reflector 31, to which the socket of the lamp is detachably connected by means of a bayonet-joint 32, said reflector being fastened at its larger end to the metal plate 60. An opaque glass plate 34 is interposed between the lamp and the negative N.

The diapositive D, which is usually in the 105 form of a glass plate coated with a suitable sensitizing emulsion, is brought into printing position against the negative N in the following manner: The crank 4 is first moved into the position indicated in dotted lines in 110 Fig. 1, in order to unlock the supporting arm 9, which can then be swung away from frame 1, carrying the plate 16 and felt cushion 17 with it. Plate 16 is designed to 115 coact with three knives or equivalent devices 40, 41 and 42 which engage the edges of the diapositive, after the latter has been placed against the cushion 17, and thus accurately support it in position during the subsequent inward movement of the plate and crank. 120 To prevent displacement of the diapositive relative to said knives, a pair of small two-armed levers 43 and 44 is mounted on pins 54 and 55 arranged in slots or kerfs formed in the two upper side portions of frame 1 125 opposite the knives. These levers are acted on by springs 45 and 46 (Figs. 3 and 4) which tend to press the inner ends of the levers toward the center of the frame so that they will be caused to bear against the up- 130

per edges of the diapositive; such engagement being normally prevented, however, by reason of the fact that the outer arms of the levers are provided with adjustable stop screws 47 and 48 which contact with a skeleton frame 49, whereby the rocking movement of the levers under the influence of springs 45 and 46 is checked. Frame 49 is disposed in front of frame 1 and is pivotally suspended from a bolt or rod 50; a depending extension or arm being formed on frame 49 which is interposed between arms 2 and 9 (Figs. 1 and 2) and which is loosely connected with the first-mentioned arm 2 through the agency of a screw 52 and intermediate spring 51, the latter tending to force the movable frame 49 away from the fixed frame 1.

The frame 49 is pressed inwardly toward frame 1 against the tension of spring 51, when the crank 4 is swung upwardly into locking position, for which purpose there is provided on the supporting arm 9 an adjustable bolt 53. This bolt is designed to engage the extension or arm on frame 49 and, as the inward movement of arm 9 continues, due to the coaction between cam 7 and nose 8, to gradually effect the desired inward movement of said frame, which latter is thereby moved away from stops 47 and 48. The springs 45 and 46 are thereupon enabled to rock the levers in the manner above-described, with the result that the edges of the diapositive are pressed against the knives. When the supporting arm 9 is subsequently unlocked, consequent upon the movement of crank 4 into its dotted-line position, and then swung away from the board, frame 49 will be forced outward by spring 51 and, hence, will again engage the stop screws on the clamping levers. This operation will be facilitated if the board O is swung into the position represented in full lines in Fig. 5, as in such position the outward movement of the supporting arm will take place automatically under the influence of gravity, assisted to some extent, perhaps, by the expansive action of spring 51.

On the other hand, if it is necessary to adjust the negative, the board should be adjusted to the position shown in dotted lines in Fig. 5; and in placing the negative opposite the diapositive, a non-actinic screen 56 (Figs. 1, 2 and 4) should be utilized. This screen is preferably mounted in a sector-shaped member 39, which is pivoted at 57 to the board and is provided with an operating arm 58 designed to be engaged, when in one position, and held against displacement by means of a spring catch 59. Said member is arranged against the inner face of plate 60 and is adapted to travel in a recessed portion thereof indicated at 38 (Figs. 2, 3 and 4); and when in the position just mentioned, which is indicated in dotted lines in

Fig. 1, the screen will be interposed between the lamp and the glass plate 25, so that it will protect the negative and the diapositive against the action of the light rays.

I claim:

1. An apparatus for printing a succession of exactly-registering diapositive images on a single plate, comprising a frame having an opening therein; means for supporting a negative in said opening; and means, separate from the first-named-supporting means, for supporting in said opening the diapositive plate to be printed upon the second-named supporting means embodying a set of supporting projections on the frame having edges which abut transversely against the edges of the diapositive plate. 70

2. An apparatus for printing a succession of exactly-registering diapositive images on a single plate, comprising a frame having an opening therein; means for supporting a negative in said opening; a set of three supporting knives having their edges arranged to transversely engage the edges of the diapositive plate to be printed upon; and means for pressing said plate edgewise against said knives. 85

3. An apparatus for printing a succession of exactly-registering diapositive images on a single plate, comprising a frame having an opening therein; means for supporting a negative in said opening; supporting projections for engagement with the edges of the diapositive plate to be printed upon; and means for imposing a yielding pressure 95 100 edgewise on said plate in a direction to hold it against said projections.

4. An apparatus for printing a succession of exactly-registering diapositive images on a single plate, comprising a frame having an opening therein; means for supporting a negative in said opening; supporting means for engagement with the edges of the diapositive plate to be printed upon; and means for moving said plate along said supporting means into said opening. 105 110

5. An apparatus for printing a succession of exactly-registering diapositive images on a single plate, comprising a frame having an opening therein; means for supporting a negative in said opening; supporting projections for engagement with the edges of the diapositive plate to be printed upon; a supporting member for moving the diapositive plate along said projections into 115 120 said opening; a pivotally-mounted carrier to which said supporting member is attached; a cam element for operating said carrier; and a crank for actuating said cam.

6. An apparatus for printing a succession of exactly-registering diapositive images on a single plate, comprising a frame having an opening therein; means for supporting a negative in said opening; a supporting member for the diapositive plate to be 125 130

printed upon to move it into said opening; a rocking carrier having said supporting member connected to its upper end and having a pivotally-mounted, forked lower end 5 provided with a projection; and a rotatably-mounted operating crank having a spiral cam for engagement with said projection.

7. An apparatus for printing a succession of exactly-registering diapositive images on 10 a single plate, comprising a frame having an opening therein; means for supporting a negative in said opening; supporting projections for engagement with the edges of the diapositive plate to be printed upon; 15 and a set of spring-actuated levers for imposing a yielding pressure edgewise against said plate in a direction to hold it against said projections.

8. An apparatus for printing a succession 20 of exactly-registering images on a single plate, comprising a frame having an opening therein; a frame mounted in said opening for supporting the negative to be printed from a glass plate arranged in the second- 25 named frame and against which the negative is disposed; a carrier for the diapositive to be printed upon movable into printing position in said opening; means for holding said carrier in such position; and a cushion in 30 said second-named frame interposed between the back thereof and the glass plate for pressing the latter and the negative against the first-named frame.

9. A photographic printing apparatus of 35 the character described, comprising in combination a pivotally-mounted board having an opening therein; a frame attached to said board and provided with a plurality of knife edges; means for resiliently pressing against 40 said edges the edges of the positive plate to be printed upon; a glass plate associated with said frame and against which the negative plate to be printed from is pressed; a source of light; and a non-actinic light 45 screen for screening said light source and facilitating the mutual adjustment of the negative and positive plates.

10. A photographic printing apparatus of the character described, comprising in combination a frame provided with a plurality 50 of knife edges; means for resiliently pressing against said edges the edges of the positive plate to be printed upon; a glass plate associated with said frame and against which the negative plate to be printed from 55 is pressed; a carrier for the positive plate provided with a recess in its inner face; a disk swiveled in said recess; a yielding cushion attached to said disk for maintaining close contact between the positive and negative plates; and a supporting arm for 60 said carrier mounted for pivotal movement in a plane perpendicular to the plane of said frame.

11. A photographic printing apparatus of 65 the character described, comprising in combination a frame provided with a plurality of knife edges; spring-pressed levers for resiliently pressing against said edges the edges of the positive plate to be printed 70 upon; a glass plate associated with said frame and against which the negative plate to be printed from is pressed; and means for maintaining the positive and negative plates in close contact. 75

12. A photographic printing apparatus of the character described, comprising in combination a frame provided with an opening; a frame for supporting the negative to be printed from; pivotally mounted within 80 said opening for movement toward and away from the first frame; a glass plate arranged in the second-named frame and against which the negative is disposed; and a screw device for adjusting the position of 85 said second-named frame with respect to said first frame.

In testimony that I claim the foregoing as my invention, I have signed my name in presence of two subscribing witnesses.
